US00D958595S

(12) **United States Design Patent** (10) **Patent No.:** **US D958,595 S**
(45) **Date of Patent:** **** Jul. 26, 2022**

(54) **COFFEE DRIPPER**

(71) Applicant: **HARIO Co., Ltd.**, Tokyo (JP)

(72) Inventor: **Miki Yoshida**, Tokyo (JP)

(73) Assignee: **HARIO CO., LTD.**, Tokyo (JP)

(**) Term: **15 Years**

(21) Appl. No.: **29/690,483**

(22) Filed: **May 8, 2019**

(30) **Foreign Application Priority Data**

Nov. 9, 2018 (JP) 2018-024645

(51) **LOC (13) Cl.** **07-06**

(57) **CLAIM**

The ornamental design for a coffee dripper, as shown and described.

DESCRIPTION

FIG. 1 is a front perspective view for a coffee dripper showing the new design;

FIG. 2 is a front view thereof;

FIG. 3 is a rear view thereof;

FIG. 4 is a top view thereof;

FIG. 5 is a bottom view thereof;

FIG. 6 is a left-side view thereof; and,

FIG. 7 is a right-side view thereof.

The broken lines showing portions of the coffee dripper form no part of the claimed design.

1 Claim, 7 Drawing Sheets
